UNITED STATES PATENT OFFICE

126,379

DESIGN FOR A HAIRBRUSH

Charles E. Dawson, Holyoke, Mass., assignor to Pro-phy-lac-tic Brush Company, Northampton,
Mass., a corporation of Delaware

Application January 28, 1941, Serial No. 98,465

Term of patent 3½ years

To all whom it may concern:

Be it known that I, Charles E. Dawson, a citizen of the United States of America and a resident of Holyoke, Hampden County, Commonwealth of Massachusetts, have invented a new, original, and ornamental Design for a Hairbrush, of which the following is a specification, reference being had to the accompanying drawing, forming part thereof.

In the drawing:

Fig. 1 is a side elevational view of a hairbrush showing my new design;

Fig. 2 is a section taken substantially on the line 2—2, Fig. 1;

Fig. 3 is a top plan view of Fig. 1;

Figs. 4 and 5 are sections taken substantially on the lines 4—4 and 5—5, respectively, Fig. 3.

The dominant features of my design reside in the portions shown in full lines.

I claim:

The ornamental design for a hairbrush, substantially as shown and described.

CHARLES E. DAWSON.
